CLAIM

The ornamental design for a modular display support frame, as shown and described.

DESCRIPTION

FIG. 1 is a first perspective view of a modular display support frame showing our new design;

FIG. 2 is an enlarged view of portion 2 of FIG. 1;

FIG. 3 is a second perspective view of FIG. 1;

FIG. 4 is an enlarged view of portion 4 of FIG. 3;

FIG. 5 is a third perspective view of FIG. 1;

FIG. 6 is an enlarged view of portion 6 of FIG. 5;

FIG. 7 is a fourth perspective view of FIG. 1;

FIG. 8 is an enlarged view of portion 8 of FIG. 7;

FIG. 9 is a fifth perspective view of FIG. 1;

FIG. 10 is an enlarged view of portion 10 of FIG. 9;

FIG. 11 a sixth perspective view of FIG. 1;

FIG. 12 is an enlarged view of portion 12 of FIG. 11;

FIG. 13 is seventh perspective view of FIG. 1;

FIG. 14 is an enlarged view of portion 14 of FIG. 13;

FIG. 15 is eighth perspective view of FIG. 1; and,

FIG. 16 is an enlarged view of portion 16 of FIG. 15.
